UNITED STATES PATENT OFFICE.

WILLIAM R. LANDFEAR, OF HARTFORD, CONNECTICUT, ASSIGNOR TO HIMSELF AND DAVID WHITTEMORE, OF SAME PLACE.

IMPROVEMENT IN MAKING EYELETS.

Specification forming part of Letters Patent No. 55,421, dated June 5, 1866.

To all whom it may concern:

Be it known that I, WILLIAM R. LANDFEAR, of the city and county of Hartford, and State of Connecticut, have made a new and useful Invention for Decapitating Eyelet-Blanks for Converting them into Eyelets; and I do hereby declare the same to be fully described in the following specification and represented in the accompanying drawings, in which—

Figure 1 is a top view, Fig. 2 a bottom view, and Fig. 3 an edge elevation, of it. Fig. 4 is a longitudinal section of the eyelet-carrier. Fig. 5 is vertical section of an eyelet-blank as it appears before being decapitated. Fig. 6 is a vertical section of such blank as it appears after decapitation.

In the said drawings, A represents a lever having a socket, *a*, made in it for holding the blank. This socket goes through the lever, in order that when the blank is placed in the socket the head of the blank, or that part which is to be removed, may extend through and beyond the socket, so as to be cut off by a knife, B, when the lever is moved, so as to cause the knife to cut across the smaller end of the socket. Both the lever and knife are connected with a supporting-plate, C, and they are arranged thereon in manner as represented, *b* being the fulcrum of the lever. The knife is parallel to the plate, and there is a space, *c*, between such plate and the knife for the lever to move in. The cutting-edge of the knife is so arranged as to cause it to cut with a drawing stroke

while it may be in action on the eyelet-blank. The plate serves to prevent the eyelet-blank from being thrown out of the socket while such blank may be in the act of being decapitated.

It is intended for the above to constitute part of a machine for making eyelets, the remainder of such machine serving to make the eyelet-blank and introduce it into the socket.

Instead of the knife being stationary and the lever being movable relatively to it, the knife may be movable relatively to the lever, and instead of the lever being used a slide-plate socketed like the lever may be employed as a substitute or equivalent.

In using the mechanism, an eyelet-blank is to be placed in the socket, and with the head of the blank extending beyond the socket, after which the lever is to be moved so as to carry the head against the knife and cause the latter to remove or cut off the projecting part or head of the blank.

I claim—

The combination and arrangement of the lever or its equivalent, the socket, and the knife, or the same and the supporting-plate, the same being to operate substantially in manner and for the purpose as set forth.

WM. R. LANDFEAR.
